FOOT CORRECTIVE ATTACHMENT FOR SHOES

Elbert F. Thomas, Wichita Falls, Tex.

Application April 10, 1943, Serial No. 482,619

2 Claims. (Cl. 36—71)

This invention consists of foot corrective means applicable to shoes, having for an object to provide a removable insert anchored in the shoe in a manner to prevent casual displacement, when in use, and although directly engageable with the foot, permits toe freedom, with a complete absence of friction and pressure.

It is further within the contemplation of this invention to utilize a shoe of special construction, the forepart of the shoe being deeper, thereby adequately accommodating the corrective means without crowding the foot.

Where an exact or so called "perfect" fit is desired, as for use on abnormal feet, the corrective means is molded over the foot cast of the individual; however, since the means is susceptible of adjustment fore and aft in the shoe, and further since the means, a rubber or plastic pad, may be ground off thinner or molded thicker, a standard pad is sufficient for average feet.

After much experimentation, I have found that a corrective pad of this teaching is characterized by sound mechanical principles. This is especially true in that with use of the invention, the long arch of the foot is anchored at the contact points, the heel anchored by the shoe counter, and the ball of the foot anchored, preventing forward stretching in addition to the advantages already herein set forth. The pad also induces lateral balance, effecting walking stress through the longitudinal center of the shoe rather than off center toward the sides of the shoe.

Other objects of the invention will be apparent from the following description of the present preferred form of the invention, taken in conjunction with the accompanying drawing, wherein

Figure 1 is a longitudinal sectional view of a shoe of special construction, illustrating the application of the corrective pad of this invention;

Figure 2 is a top plan view of the corrective pad per se, and

Figure 3 is a transverse sectional view of the pad taken on the line 3—3 of Figure 2.

In order to illustrate the application of this invention, I have in Figure 1 of the drawing, shown a shoe 4 which is of standard construction, except that the forepart of the sole, directly in advance of the arch of the shoe, is dipped downwardly, as indicated at 5, forming a longitudinal arc. A shoe upper 6 is engaged with the sole in the usual manner. By dipping the sole in the manner above described, the forepart of the shoe is deepened and is adapted to accom-

modate the corrective means constituting the present invention, generally designated 7.

The corrective means consists of a pad made of rubber, plastic, or other suitable material and is of a shape conforming substantially to the shape of the inner face of the shoe sole. The forward end 8 of the pad fits snugly against the forward inner wall of the shoe, while the rear margin 9 is tapered to a fine edge which terminates at approximately the inception of the shoe arch. The body of the pad is thickened, as indicated at 10, a portion of the upper surface thereof issuing into an arcuate rib or protuberance 11, the ends of which fall short of the marginal edges of the pad. The rib is adapted for engagement beneath the base of the innermost phalange of each of the small toes, as illustrated in Figure 1. The great toe of the foot is adapted to clear the inner end of the rib. The upper face of the pad 7 is extended upwardly at its margin to provide a flange 12, as illustrated to advantage in Figure 3.

Since the pad conforms substantially to the contour of the shoe, there will be no creeping or casual displacement of the pad when in use. However, the pad is susceptible of limited fore and aft adjustment to better adapt its use in varying foot conditions. Furthermore, by permitting removal of the pad, cleansing and medication of the latter may be had, if and when desired.

While I have herein described a preferred form of the invention, and certain advantages thereof, it is nevertheless to be understood that changes may be made within the scope of the claims hereto appended.

What is claimed is:

1. Corrective means for shoes including a resilient pad engageable with a shoe sole and conforming substantially to the shape of the sole, an integral resilient protuberance on the pad located between the ball of the foot and the pads of the toes, the ends of which fall short of the lateral margins of the pad, and a foot embracing flange extending substantially around the margin of the pad.

2. Corrective means for shoes including a resilient pad engageable with a shoe sole and conforming substantially to the shape of the sole, and an integral resilient protuberance on the pad, located between the ball of the foot and the pads of the toe, the ends of which fall short of the lateral margins of the pad.

ELBERT F. THOMAS.
